Primary Examiner — R. Johnson(74) *Attorney, Agent, or Firm* — SoCal IP Law Group
LLP; Guy Cumberbatch; Mark Goldstein(57) **CLAIM**

The ornamental design for a fabric chair cover, as shown and described.

DESCRIPTION

FIG. 1 is a top perspective view of a fabric chair cover showing my new design; the fabric chair cover shown as used with a collapsible chair base;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a bottom perspective view thereof;

FIG. 9 is a top plan view of the fabric chair cover; and,

FIG. 10 is a bottom plan view thereof.

The broken lines illustrate a collapsible chair base to which the fabric chair cover is attached and form no part of the claimed design.
